UNITED STATES PATENT OFFICE.

EDWARD CRAIG, OF ST. JOSEPH, MICHIGAN, ASSIGNEE TO SARANAC MACHINE COMPANY, OF BENTON HARBOR, MICHIGAN, A CORPORATION OF MICHIGAN.

PACKAGE-CAPPING MACHINE.

1,248,083.

Specification of Letters Patent. Patented Nov. 27, 1917.

Application filed January 17, 1914. Serial No. 812,628.

To all whom it may concern:

Be it known that I, EDWARD CRAIG, a citizen of the United States of America, and resident of St. Joseph, Berrien county, Michigan, have invented a certain new and useful Improvement in Package-Capping Machines, of which the following is a specification.

My invention relates to machines for closing the heads or ends of packages. For example, in the preparation of food packages, such as those containing breakfast foods, pasteboard boxes are employed, and the ends of these boxes are sealed after the boxes are filled with the food. In order to properly seal packages of this kind against the entrance of vermin, etc., it has been proposed to place a paper cap on each end of the box, inside of the wrapper, to thereby overcome this difficulty. My invention relates more particularly to machines for automatically applying these paper caps to the food packages, in order to render the same vermin proof, and preliminary to the application of the wrappers to said packages.

Generally stated, the object of my invention is to provide a novel and highly efficient machine which will automatically provide the packages with caps or end coverings of the desired character, in a rapid and effective manner, and with as little additional expense as possible.

A special object is to provide a machine of this kind in which the packages are automatically fed into position to receive the paper caps, and in which the paper from which the caps are made is automatically fed from rolls, or in any other suitable manner, whereby the packages are automatically capped without any necessity of handling or manual manipulation thereof.

Another object is to provide a novel and improved folding and pasting mechanism, in a machine of this kind, which will insure a perfectly tight and effective sealing of the ends of the packages, more especially at the corners thereof, and whereby the caps thus formed for the packages will not interfere with the subsequent application of the paper wrappers.

It is also an object to provide certain details and features of construction and novel

combinations tending to increase the general efficiency and serviceability of a box or package sealing or capping machine of this particular character.

To the foregoing and other useful ends my invention consists in matters hereinafter set forth and claimed.

In the accompanying drawings Figure 1 is a plan of a capping machine embodying the principles of my invention. Fig. 2 is a side elevation of said machine. Fig. 3 is a rear end elevation of the machine shown in Figs. 1 and 2, with certain portions thereof broken away for convenience of illustration. Fig. 4 is an enlarged front elevation of a portion of the said machine, showing certain parts thereof in section, and illustrating the position of the package (in dotted lines) before the application of the caps thereto, and during the said operation, the two sheets of paper being shown fed into position at opposite ends of the package. Fig. 5 is a view similar to Fig. 4, but showing the positions of the different parts during the folding operation. Fig. 6 is an enlarged plan view of the paper feeding and paste applying mechanism which is disposed above the machine, and which is omitted from Fig. 1 for convenience of illustration. Fig. 7 is a vertical section on line 7-7 in Fig. 3. Fig. 8 is an enlarged vertical section of the upper portion of the machine, illustrating the automatic feed mechanism for feeding the packages into position for receiving the caps, and also illustrating the construction and mode of operation of a portion of the means by which the paper is automatically pulled downward at each end of the package. Fig. 9 is an enlarged section on line 9-9 in Fig. 1, showing the right hand portion of the machine broken away for convenience of illustration, it being understood that these omitted parts are like those shown in this figure, except that they are reversed or turned end for end. Fig. 10 is a horizontal section on line 10-10 in Fig. 7. Fig. 11 is an enlarged detail perspective view of a portion of the mechanism for folding paper upon and about the square ends of the package. Fig. 12 is a section on line 12-12 in Fig. 6, showing the central portion of the horizontal connecting shaft broken away for

convenience of illustration. Fig. 13 is an enlarged front elevation of the mechanism shown at the left in Fig. 12, illustrating the form and character of the pivoted member 5 by which the two rolls are separated when it is desired to remove or shift the paper.

Fig. 14 is a perspective of the package with the two paper caps applied thereto. Fig. 15 is a plan of the mechanism shown in Fig. 16. Fig. 16 is a detail sectional view, on a large scale, on line 16-16 in Fig. 15. Fig. 17 is a detail sectional view on line 17-17 in Fig. 9. Fig. 18 is a perspective of one of the elements of the folding mechanism. Fig. 19 is a perspective of another element of the folding mechanism. Fig. 20 is a perspective of the package, showing the manner in which the rectangular sheets of paper are applied to the ends thereof, the 20 machine operating to fold the upper and lower edges first, and the side edges being folded last. Fig. 21 is a detail sectional view, in a horizontal plane, of one of the grippers by which the two sheets of paper 25 are pulled downward in front of the opposite ends of the package. Fig. 22 is a fragmentary or detail sectional view showing the vertically reciprocating element by which the packages are lowered one by one 30 from the hopper into position to be pushed forward by the automatic feed mechanism.

As thus illustrated, and referring more particularly to Figs. 1, 3 and 7, it will be seen that my invention comprises a body 35 frame composed of upright side castings, A, which are mounted on a base, a, being properly spaced apart to provide space between them for certain operative elements of the machine. The top of the body frame 40 thus provided is formed by a table, B, having parallel guides, b, at the rear end thereof, said guides providing a horizontal way for the reciprocating plunger, C, which latter travels back and forth on said table. 45 Above the said guide way and plunger a belt pulley, c, is mounted to rotate about a horizontal axis, being provided with a flat belt, c¹ upon which the packages are placed by the attendant, and whereby the said packages 50 are fed to the chute or hopper, c², which latter is composed of curved bars forming a passage or hopper-like space between them. With this arrangement, the packages are fed forward and then downward, the 55 lowermost package being held in waiting position above the plunger, C, by the vertical reciprocating shoulders, c³ (see Fig. 22) until after the said plunger has moved to the extreme right in Fig. 7, and at which 60 time the said shoulders, c³, move downward to bring the package onto the table and directly in front of said plunger. The said shoulders, c³, are mounted on vertically disposed rods, c⁴, which have their lower ends 65 fixed in a cross bar or yoke, c⁵, disposed be-

low the table, it being observed that the said rods extend up and down at opposite sides of the said table and guideways for the plunger. The vertical reciprocating rod, c⁶, is mounted in a bearing, c⁷, on the frame 70 or body of the machine, and the lower end of this rod has a link connection, c⁸, with the end of the bell crank lever, c⁹, which is mounted to rock on the shaft, c¹⁰, and which is connected by a pitman, c¹¹, with the rotary cam, c¹², on the main drive shaft, D, which latter is disposed at the bottom of the machine and supported in suitable bearings carried by the said frame thereof. The 75 said pitman has a roll or projection, c¹³, (see Fig. 8) which engages in a groove formed in the face or side of said cam, whereby the bell crank lever, c⁹, is operated to cause the rod, c⁶, to reciprocate vertically. This, as stated, is properly timed to move the shoulders, c³, with the waiting package thereon, downward immediately after the plunger, C has moved to the right. The said plunger is connected by a link, c¹⁴, with the bell crank lever, c¹⁵, which is mounted to rock 80 on the said shaft, c¹⁰, and which is in turn connected by a pitman, c¹⁶, with the cam, c¹⁷, which latter is also mounted on said drive shaft and provided with a suitable cam groove for engaging and operating said 85 pitman in a manner that will be readily understood. Thus, the package feeding mechanism is operated automatically from the shaft, D, and in a manner to successively push the packages forward and into a position to have the paper caps applied thereto. It may also be stated, at this point in the 90 description of the construction and operation of the machine, that the package to which the caps have been applied is pushed 95 forward by the next package. The 100 capped package is pushed onto the traveling belt, E, which operates to then convey the package to a point any desired distance from the machine. This belt, E is driven by 105 a sprocket chain, e, extending to a sprocket on the shaft, D, in the manner shown more clearly in Fig. 7. A sprocket wheel on the shaft, e¹, is then connected by a sprocket chain, e², with a sprocket on the shaft, c¹⁰, 110 in the manner shown. A smaller sprocket on the shaft, c¹⁰, is then connected by a sprocket chain, e³, with a sprocket on the shaft, e⁴, whereby the pulley, c, is rotated 115 in the direction indicated. The packages 120 in the hopper, c², are stationary while the folding operation is being performed on the package which has been fed into position. Before the plunger, C, moves forward, however, the shoulders, c³, move downward, 125 thereby causing all of the packages in the hopper to move forward and downward, bringing the lowermost package into position to be pushed forward by the plunger, C, in the manner explained. While the said 130

plunger, C, is moving backward and to the right, as shown in Fig. 7, the shoulders, c^3 , are again supporting the lowermost package, the said shoulders having been caused to move upward at the proper time. Thus the top of the plunger, C, is relieved of the weight of the packages, the latter being supported independently of the said plunger, and in a way that enables the plunger to work freely and smoothly and without undue friction.

The means for holding the package in position, while the paper caps are being applied thereto, is as follows:

Referring to Fig. 8, it will be seen that the table B is provided with tracks F, upon which the packages are pushed forward by the plunger C, and horizontal plate f for receiving said packages. A vertically disposed plate f^1 is provided with an opening through which the packages are pushed onto the plate f, and at the other side of the said supporting plate f a yielding stop f^2 is arranged in position to limit the forward movement of the package, said stop being pivoted at its lower end and yieldingly held in normal position by a spring f^3 , whereby each package may be pushed off from plate f, when finished, by the next or succeeding package. As soon as a package has been capped, it is then pushed over the stop f^2 , as the latter swings outward and downward under the pressure. As soon as this package is out of the way said stop then springs back into normal position to hold the fresh package in place. Pressure is exerted upon the top of each package by the shoe or plate f^4 , which is carried on vertically disposed rods f^5 , in the manner shown in Fig. 7. These rods f^5 are mounted to reciprocate in the stationary supporting plate f^6 , which latter is disposed over the position in which the package is held while being capped. Springs f^7 are applied to said rods at points between the plates f^4 and f^6 , whereby the said plate f^4 is yieldingly held upon the package. Preferably, and as shown, the forward edge of the plate f^4 is turned up at f^8 for the purpose of enabling the packages to slide readily below said plate. Thus the packages are squarely and effectively held in position to have the paper caps applied thereto.

The means for folding and applying the paper caps to the ends of the paper packages are as follows:

Referring to Figs. 1, 4, 5, 9, 11, 17, 18 and 19, it will be seen that the table B is provided at each side with an extension b^1 which supports the guideways b^2 in alignment with each other, at opposite ends of the package, when the latter is in position for receiving the caps. As the folding mechanism at one side of the machine is exactly the same as the folding mechanism at the other side, a description of the mechanism

shown at the left in Fig. 1 will be sufficient. Referring, therefore, to Fig. 9, it will be seen that the said guideway b^2 has mounted thereon a horizontally disposed plunger G which is hollow, and square in cross-section, 70 as indicated in Fig. 17, said plunger being arranged with its end extending toward the end of the package X (indicated in dotted lines in Fig. 9) and supported for horizontal endwise reciprocating movement. At the 75 end of the inner plunger G¹ which is juxtaposed to the end of the package, it is provided with upper and lower folding plates g and g^1 which are integral with the vertically disposed plate g^2 , which latter is secured in 80 a suitable manner to the end of said plunger G¹. These folding plates g and g^1 operate first to produce the folded condition of the caps Y shown in Fig. 20—that is to say, the upper and lower edges of these rectangular 85 sheets of paper are folded upon the upper and lower surfaces of the package in the manner shown. The said folding plates g and g^1 are provided at each side edge thereof with rollers g^3 . The plunger G is connected by a link g^4 with a bell crank lever g^5 which latter is pivoted on the frame at g^6 , as shown more clearly in Fig. 3. The lower end of this bell crank lever is connected by a link g^7 with the cam device g^8 on the shaft 90 D, which cam device can be of any suitable character. With this arrangement the rotation of said shaft D serves to reciprocate the plunger G toward and away from the end of the package. A rod g^9 extends longitudinally through the plunger G¹ and is provided at its end with a plate g^{10} which bears against the paper cap Y to hold the same firmly and flat-wise against the flat end surface of the package, during the folding operation. The outer end of the rod g^9 is provided with a nut g^{11} which bears against the bumper plate g^{12} on the removable cap g^{13} which is secured upon the end of the plunger G¹, whereby backward movement 100 of the latter in a direction away from the package will cause the rod g^9 and the plate g^{10} to be restored to normal position. In order that the plungers G and G¹ may continue moving toward the package after the plate 105 g^{10} has engaged and clamped the sheet of paper upon the end of the package, the outer end portion of the plunger G¹ is provided with a chamber g^{14} which contains a spring 110 g^{15} , said spring being in the form of a coil 115 encircling the rod g^9 . It will be seen that the said spring is interposed between a shoulder g^{16} on the said rod and another shoulder provided by the inner surface of the cap g^{13} , whereby the tension of the 120 spring is positively exerted in a manner to move the rod g^9 toward the package. The cap g^{13} is connected to the plunger G by means of springs g^{17} , two at each side of 125 said plunger (see Figs. 4 and 5), whereby 130

the said plunger g may continue moving toward the package after the plate g^2 has encountered the plate g^{10} , thus permitting the plunger G to continue its forward movement after the upper and lower folders g and g^1 have performed their function and reached the limit of their forward movement. The vertically disposed plate g^{18} is secured to the end of the plunger G , at a point outside of the plate g^2 , whereby the said plate g^2 is disposed between the plates g^{10} and g^{18} , in a manner illustrated in Fig. 9. The plate g^{18} is provided with parallel and vertically disposed side plates g^{19} , recesses g^{20} being provided between the side edges of the plate g^{18} and the inner surfaces of the plates g^{10} , in the manner shown in Fig. 18. The folding fingers g^{21} are four in number, are disposed in vertical planes, and are pivoted to the plates g^{19} at g^{22} , whereby said fingers are so arranged that their forward end portions g^{23} are adapted to swing up and down. Springs g^{24} are applied to the pivotal mountings of said fingers, in any suitable manner, whereby each finger slides on the inner surface of one of the plates g^{19} , thereby producing sufficient friction to hold the fingers in the position shown in Fig. 9, which is the normal position, or in the operative position shown in Fig. 5. For the purpose of returning these fingers to normal position, when the plungers move backward, the rear end of each finger is provided with a cam portion g^{25} which is adapted to engage one of the upper and lower rolls g^{26} , which latter are mounted on any suitable stationary portion of the machine. When the cam portions g^{25} engage the rollers g^{26} the said fingers g^{21} are thereby moved into the position shown in Fig. 9, whereby they are thus placed in condition to be moved forward toward the package. The plates g^{19} have secured thereto extension plates g^{27} , which latter are provided with the curved folders g^{28} , which latter bend and fold the side edges of the sheets of paper forming the caps, when the plungers are moved forward. The fingers g^{21} are for the purpose of doubling over the corner portions y of the caps (see Figs. 14 and 20), after the side edges y^1 have been folded into position by the folders g^{28} . This is accomplished by engagement of the upper edges of said fingers g^{21} with the rolls g^3 , as the plunger G moves forward, whereby the said fingers are moved into the position shown in Fig. 5, thus doubling over the said corner portions y in the manner shown in Fig. 14. Thus the upper and lower edges y^2 of the caps are folded first, then the side edges y^1 , and then the corner portions y which are, of course, of double thickness. It will also be seen that the folders g^{28} are provided with rollers g^{29} which are disposed immediately behind the upper and lower edges of said folders in the manner shown in

Fig. 11, and which are arranged to rotate about vertical axes. These rollers, when the plungers move forward, help to firmly press the side edges y^1 of the caps against the sides of the package, whereby these edge portions will be made to firmly adhere to the package. Also again referring to the Fig. 5 it will be seen that these rollers g^{29} pass over the corner portions y of the caps when the plungers are retracted to normal position. Thus these corner portions y are first folded into proper position by the fingers g^{21} , and are then rolled firmly into position by the rollers g^{29} when the plungers return to normal position. Thus the sheet of paper is first clamped to the end of the package by the plate g^{10} ; the upper and lower edge portions y^2 of the cap are then folded upon the package by the folders g and g^1 ; then the folders g^{28} fold the edge portions y^1 against the package, after which the fingers g^{21} , by means of their engagement with the rollers g^3 , double over the corner portions or two-ply sections y of the caps, whereby these corner portions are caused to extend toward each other at the sides of the package; and then the said corner portions y are compressed tightly to the package by the rollers g^{29} to cause these portions of the caps to adhere to the package and thereby effectively seal the same in the desired manner. As previously explained, these operative parts are all restored to normal position as shown in Fig. 9 upon the outward movement of the upper end of the bell crank lever g^5 , whereby the mechanism is placed in position for another operation.

The means for cutting the paper, whereby rectangular sheets of the proper size for the caps are provided, is as follows:

A stationary knife H is disposed directly above the end of the package, and a little in advance thereof, as shown in Fig. 9. The coöperating movable knife h is arranged to move back and forth below the said stationary knife, and is carried on the end of a slide or movable plate h^1 , which latter is mounted in any suitable manner on some stationary portion of the machine. The said slide or plate h^1 is connected by toggle links h^2 and h^3 with the block h^4 , which latter is secured in a suitable manner to the upper surface of the plunger G , as shown in Figs. 1 and 9. The toggle joint thus formed is connected by a link h^5 with a stationary bracket arm h^6 , which latter is secured to any convenient stationary portion of the machine. The construction is such that the relative positions of these links bring the toggle joint a little off center or to one side, as shown in Fig. 1, when the folding mechanism is in normal or retracted position. When the plunger G moves forward, the knife plate or slide h^1 is also

moved forward, but at a constantly decreasing speed, owing to the control exercised by the link h^5 over the toggle joint, whereby the knife h has only sufficient movement to 5 carry it a little beyond the shearing edge of the stationary knife H , thereby cutting off the sheet of paper which is fed downward between these knives in the manner shown in Fig. 4. It will be understood, of course, that this cutting mechanism is duplicated at the other side of the machine, whereby the two sheets of paper are cut off simultaneously at opposite ends of the package, and immediately in advance of the 15 folding operation.

Means for feeding the paper into position, and for smearing the surface thereof with paste or other adhesive, are also provided, and are constructed and operated as 20 follows:

Paste receptacles I are disposed above the machine and mounted on standards i in any suitable or desired manner. As the feeding and pasting mechanism at one side of the 25 machine is identical with that at the other side, a description of one will be sufficient.

Referring therefore to Figs. 6, 12 and 13, it will be seen that the paste receptacle I shown at the left is provided with a paste 30 roll i^2 which is disposed in bearings i^2 at each side of the receptacle, and which rotates in the paste or glue or other adhesive. The shaft or axle of the said roll is connected by bevel gears I' , with the shaft i^3 , 35 whereby the corresponding roll at the other side of the machine is driven in unison with the said roll i^2 , and whereby the two long strips or sheets of paper are fed simultaneously to the previously described cutting 40 and folding devices at the opposite ends of the package. Any suitable arrangement can be employed, it will be understood, for communicating power to these paste rolls from the shaft D as, for example, by means 45 of the shaft D' and the bevel gears i^4 , i^5 and i^6 . (See Figs. 6 and 10). The bearings i^2 are provided with upwardly and outwardly extending extensions i^7 having slots i^8 in which are mounted the movable bearing 50 blocks i^9 for the clamping or idler roll i^{10} by which the paper Z is held firmly against the paste covered surface of the roll i^2 , as shown in Fig. 12. Springs i^{11} are provided for engaging the bearing blocks i^9 , whereby 55 the roll i^{10} exerts a yielding pressure against the roll i^2 , whereby the two rolls may be separated when it is desired to remove or shift the position of the paper, the two rolls being preferably geared together, by gearing I' , in any suitable manner. A bail-shaped handle i^{12} is pivoted upon the extension i^7 at i^8 in any suitable manner and arranged in position to engage the end portions i^{14} of the shaft or axle of the roll i^{10} . 60 With this arrangement, and by swinging

the said handle i^{12} outward in the direction indicated in Fig. 13, so as to engage the end portions i^{14} , the roll i^{10} is shifted away from the roll i^2 , thus permitting manipulation of the paper. It will be seen that the paper travels upward from a suitable source of supply (such as a roll not shown) to the roll i^{10} , thence downward between the two rolls i^{10} and i^2 , whereby one surface of the paper becomes coated with the paste, and thence downward and over the edge portion i^{15} , as shown in Fig. 12, before continuing downward to the cutting and folding mechanism. This edge portion i^{15} of the receptacle I scrapes off the surplus 70 paste or glue, causing the surplus to flow into the said receptacle. Previously, however, the greater part of the surplus has been removed from the surface of the paper by the pivoted scraper i^{16} which is disposed 75 in position to bear against the under side of the paper as it emerges from between the two rolls, thus causing the surplus to drop back into the receptacle. The feeding movement communicated to the paper by the 80 positive rotation of the roll i^2 is, it will be seen, of a continuous nature, but is not fast enough to overfeed the paper, and does not supply the paper faster than is necessary to form an accumulation thereof while 85 the folding operation is taking place. This accumulation of the paper takes place immediately above the knives H and h , and is produced by causing the paper to sag between the paste mechanism and the said 90 knives, whereby this sagging portion or accumulation becomes available for the next cap. For this purpose, the paper is caused to travel downward through a guide J which is disposed immediately above the 95 said knives, and which is provided with swinging fingers j which hang in position to bear against the adhesive surface of the paper at their lower ends. This guiding 100 arrangement of the paper is, of course, duplicated at the other side of the machine, and a description of the one shown in Fig. 9 will be sufficient. After the knife h has moved forward, thereby cutting off the sheet of paper, the end portion of the continuous sheet remains stationary in the guide J , whereby the continuous feeding movement of the roll i^2 causes the paper to sag between this guide and the paste 105 mechanism. For the purpose of pulling down the slack or accumulated portion of the paper, after the folding mechanism has returned to normal position, in order to bring the paper into position to be again severed by the knives, a set of vertically 110 reciprocating grippers K , four in number, are provided and arranged to grasp the lower corners of the paper. These grippers are each constructed as shown in Fig. 115 21, being composed of cooperating jaws k 120

130

and k^1 , the jaw k being fixed to the upper end of the rod k^2 , and the jaw k^1 being fixed to the upper end of the tube or sleeve k^3 which incloses said rod. The said vertically disposed tubes k^3 are clamped at their lower ends by the split end portions k^4 of the parallel and horizontally disposed bars k^5 , which latter are rigidly connected together by the parallel bars k^6 , whereby a frame is provided which is movable up and down. The rods k^2 have their lower ends secured to the crank arms k^7 , which arms extend horizontally and have their outer ends connected by links k^8 with the blocks k^9 . It will be seen that these blocks are connected in pairs by the cylindric portions k^{10} , and are arranged to slide horizontally in guideways k^{11} formed between the upper and lower bars k^6 . Vertically disposed plates k^{12} , suitably spaced apart and rigidly connected together by portions k^{13} , are arranged between the bars k^6 , in the manner shown in Fig. 15, and are provided with cam slots k^{14} , through which extend the said portions k^{10} , as shown in Fig. 16, this being the normal condition of the parts. The vertical member k^{15} is rigidly secured to plates k^{12} , and is provided at its upper end with a plate k^{16} which engages the stationary and vertically disposed guides k^{17} , which latter are suitably secured to the frame or body of the machine. The said guides k^{17} have their lower ends connected together by a plate k^{18} , this plate having an opening in which the member k^{15} reciprocates or slides up and down. Normally the parts are in the position shown in Figs. 15 and 16, whereby the four grippers K are in the positions shown in Fig. 4 being disposed at this time in a common horizontal plane a little below the package. The member k^{15} is connected by a link k^{19} with the bell crank lever k^{20} mounted on the shaft c^{10} , which lever is in turn connected by a pitman k^{21} with the cam mechanism k^{22} on the shaft D, which mechanism may be of any suitable known or approved character. With this construction, and when the shaft D rotates, the long arm k^{20} of the bell crank lever moves up and down, thereby causing the link k^{19} to move the member k^{15} up and down. The said cam mechanism k^{22} , and the said connections, are so timed in their operation that the member k^{15} starts upward while the folding mechanism is operating on the ends of the package, the slide or knife plate h^1 being provided at each side edge thereof with a notch k^{23} through which the grippers K pass while moving upward. In this way the said grippers assume a waiting position in a horizontal plane immediately above the knife plate h^1 , being open at this time, in the manner shown in Fig. 21. As soon as the cutting and folding mechanism has

been retracted to normal position, as shown in Fig. 4; the grippers K are then closed by the downward movement of the member k^{15} , it being observed that the downward movement of the plates k^{12} takes place while 70 the bars k^6 are standing still, by reason of the fact that the tubes or sleeves k^3 extend upward through friction boxes k^{24} , which latter may be of any suitable character. The cam slots k^{14} are disposed at such an angle, 75 as will be seen, (see Fig. 16) that the downward movement of the plates k^{12} causes the cylindric portions k^{10} to move away from each other, thereby rotating the rods k^2 in a direction to close the jaws k^1 of the grippers, by movement of the jaw k from the position shown in dotted lines in Fig. 21 to the position in full lines. When the portions k^{10} reach the upper ends of the slots k^{14} , the bars k^6 then begin to move downward, 80 and the said grippers K having been closed upon the sheets of paper, by the rotation of the rods k^2 , in the manner explained, it necessarily follows that the two sheets of paper are jerked downward and 85 into the positions shown in Fig. 4; it being understood that the groove of the cam mechanism k^{22} can be of such character that the grippers K are caused to open a little, by slight upward movement of the member k^{15} , as soon as said grippers have 90 reached the limit of their downward movement. In other words and by reason of the lost motion connections provided by the slots k^{14} and cylindric portions k^{10} , the member k^{15} and the plates k^{12} move upward a distance before the grippers K begin to move in the same direction, and vice versa, 95 when the cam mechanism k^{22} begins to move the member k^{15} downward, the said grippers then remain in their elevated positions 100 before partaking of the said downward movement. It is in this way, and by this lost motion connection, that the said grippers are opened and closed automatically, 105 whereby the paper is gripped and pulled downward, and is then released in order to permit the clamping plates g^{10} to clamp the severed end portions of the paper strips 110 against the ends of the package, in the manner previously explained. It will be understood, of course, that various expedients can 115 be employed with a view to timing the different parts in their operation for the purpose of causing the different steps involved 120 in the general operation to occur in their proper sequence, and in the manner and for the purpose explained. At the time that the grippers K grip the corner portions of the strips of paper, and before the said grippers begin to move downward, an accumulation 125 of the paper has been produced between the guides J and the paste mechanism, causing a sagging of the paper, owing to the continuous operation of the paste 130

rolls. This accumulation or slack portion of the paper is immediately taken up or eliminated by the downward movement of the grippers; and while the folding operation is taking place in the manner described, the paste rolls are again feeding the paper to produce enough slack or sag therein to afford sufficient paper for the next set of caps.

10 From the foregoing it will be seen that by my invention I provide a machine which is capable of automatically capping the packages without the necessity of any handling or manual manipulation thereof. The packages are fed to the folding mechanism, in the manner previously described, and are delivered from the machine in a properly capped or sealed condition. The paper employed for the caps may be of any suitable 15 or desired character, but is preferably of a light and flexible character, whereby the various cutting and folding operations are easily performed in the desired manner, and whereby the cost of capping the packages is 20 practically reduced to a nominal amount. Each cap, as described, is formed from a square or rectangular section of the paper, automatically cut from the downwardly fed sheet. Also, and as shown, the relative arrangement of the parts is preferably such 25 that the folded edge portions y^2 of the caps extend over onto the upper and lower surfaces of the package to a greater extent than do the folded edge portions y^1 at the sides 30 of the cap. In this way, and as shown, the corner portions or two-ply sections y adhere directly to the side surfaces of the package, as well as to the portions y^1 of the cap. This insures an effective and tight sealing 35 of the ends of the package and results in a formation and construction of the cap which holds it in place. It will be understood, of course, that each package, after being supplied with these vermin-proof end caps, is 40 then provided with a paper wrapper which is folded and sealed at the ends of the package. Thus, by my invention, I make it possible to cap the packages by machinery, in a rapid and inexpensive manner, and in 45 a way that renders unnecessary any effort to make the regular or outside wrapper of the package in any way vermin-proof. In other words, the pasteboard box filled with food, such as oatmeal, is supplied with end caps 50 of thin paper, by the mechanical operations heretofore described, and in a manner that then and there renders the package entirely vermin-proof. Consequently, and as stated, the subsequent wrapping of the package 55 does not involve any provision for rendering the packages vermin-proof, as this contingency has been taken care of by the capping and sealing of the ends of the package. With a machine of the foregoing character 60 no complicated cutting of the paper is re-

quired, as in each case only a straight cut is necessary for each cap. In other words, a machine of this character is capable of converting a square or rectangular section of paper into a rectangular cap having flanges 70 along the four sides thereof, which flanges are caused by the machine to adhere to the flat sides of the package, thus obviating the necessity of any cutting operations for the corners of the caps.

75 I do not limit myself to the exact construction shown and described.

What I claim as my invention is:—

1. A capping machine for sealing the ends of packages, comprising means for holding 80 a package in position to receive the cap, mechanism for feeding sheet material on to the end of the package, a clamp for holding the sheet in position, instrumentalities for folding the marginal portions of the sheet 85 upon the sides of the package, thereby forming outstanding sections of the material between said portions, and devices for folding each section upon one of said portions while the package is still in said position. 90

2. The said machine (substantially as set forth in claim 1), and provisions for simultaneously applying a similar cap to the other end of the package.

3. The said machine (substantially as set 95 forth in claim 1), and provisions for applying an adhesive to the entire inner surface of said sheet before the same is fed into position.

4. The said machine (substantially as set 100 forth in claim 1), and provisions for automatically feeding the packages to said means.

5. The said machine (substantially as set 105 forth in claim 1), and provisions for cutting the said sheet from a strip, operative to sever the material in advance of the operation of said clamp.

6. The said machine (substantially as set 110 forth in claim 1), the said instrumentalities being operative to fold said portions along straight lines to locate each section at one corner of a rectangle, and said devices operating to press together two parts of each section.

7. The said machine (substantially as set 115 forth in claim 1), and provisions for simultaneously applying a similar cap to the other end of the package, the said instrumentalities being operative to fold said portions along straight lines to locate each section at one corner of a rectangle, and said devices operative to press together two parts of each section.

8. The said machine (substantially as set 120 forth in claim 1), and provisions for applying an adhesive to the entire inner surface of said sheet before the same is fed into position, the said instrumentalities being operative to fold said portions along straight 125

lines to locate each section at one corner of a rectangle, and said devices operative to press together two parts of each section.

9. The said machine (substantially as set forth in claim 1), and provisions for automatically feeding the packages to said means, the said instrumentalities being operative to fold said portions along straight lines to locate each section at one corner 10 of a rectangle, and said devices being operative to press together two parts of each section.

10. The said machine (substantially as set forth in claim 1), and provisions for 15 cutting the said sheet from a strip, operative to sever the material in advance of the operation of said clamp, the said instrumentalities being operative to fold said portions along straight lines to locate each section 20 at one corner of a rectangle, and said devices operative to press together two parts of each section.

11. A capping machine for sealing the ends of packages, comprising means for holding a package in position to receive the cap, mechanism for feeding sheet material on to the end of the package, a clamp for holding the sheet in position, instrumentalities for 25 folding the marginal portions of the sheet 30 upon the sides of the package, thereby forming outstanding sections of the material between said portions, and devices for folding each section upon one of said portions, said instrumentalities being operative to fold said portions along straight 35 lines, and said devices operating to fold the sections toward each other.

12. A capping machine for sealing the ends of packages, comprising means for 40 holding a package in position to receive the cap, mechanism for feeding sheet material on to the end of the package, a clamp for holding the sheet in position, instrumentalities for folding the marginal portions of 45 the sheet upon the sides of the packages, thereby forming outstanding sections of the material between said portions, and devices for folding each section upon one of said portions, and provisions for simultaneously 50 applying a similar cap to the other end of the package, said instrumentalities being operative to fold said portions along straight lines, and said devices operating to fold the sections toward each other.

55 13. A capping machine for sealing the ends of packages, comprising means for holding a package in position to receive the cap, mechanism for feeding sheet material on to the end of the package, a clamp for 60 holding the sheet in position, instrumentalities for folding the marginal portions of the sheet upon the sides of the package, thereby forming outstanding sections of the material between said portions, and devices

for folding each section upon one of said 65 portions, and provisions for applying an adhesive to the entire inner surface of said sheet before the same is fed into position, said instrumentalities being operative to fold said portions along straight lines, and 70 said devices operating to fold the sections toward each other.

14. A capping machine for sealing the ends of packages, comprising means for holding a package in position to receive the 75 cap, mechanism for feeding sheet material on to the end of the package, a clamp for holding the sheet in position, instrumentalities for folding the marginal portions of the sheet upon the sides of the package, thereby 80 forming outstanding sections of the material between said portions, and devices for folding each section upon one of said portions, and provisions for automatically 85 feeding the packages to said means, said instrumentalities being operative to fold said portions along straight lines, and said 90 devices operating to fold the sections toward each other.

15. A capping machine for sealing the 90 ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby 95 forming outstanding sections of the material between said portions, and devices for folding each section upon one of said portions, and provisions for cutting the said 100 sheet from a strip, operative to sever the material in advance of the operation of said clamp, said instrumentalities being operative to fold said portions along straight 105 lines, and said devices operating to fold the sections toward each other.

16. A capping machine for sealing the ends of packages, comprising means for holding a package in position to receive the 110 cap, mechanism for feeding sheet material on to the end of the package, a clamp for holding the sheet in position, instrumentalities for folding the marginal portions of the sheet upon the sides of the package, thereby 115 forming outstanding sections of the material between said portions, and devices for folding each section upon one of said portions, the said instrumentalities including a pair of folders for opposite sides of the package, a pair of folders for the other sides, and means whereby said folders have motion in unison, having provision for allowing one pair to move relatively to the other.

17. A capping machine for sealing the ends of packages, comprising means for holding a package in position to receive the 120

cap, mechanism for feeding sheet material on to the end of the package, a clamp for holding the sheet in position, instrumentalities for folding the marginal portions of the sheet upon the sides of the package, thereby forming outstanding sections of the material between said portions, and devices for folding each section upon one of said portions, and provisions for simultaneously applying a similar cap to the other end of the package, the said instrumentalities including a pair of folders for opposite sides of the package, a pair of folders for the other sides, and means whereby said folders have motion in unison, having provision for allowing one pair to move relatively to the other.

18. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, and devices for folding each section upon one of said portions, and provisions for applying an adhesive to the entire inner surface of said sheet before the same is fed into position, the said instrumentalities including a pair of folders for opposite sides of the package, a pair of folders for the other sides, and means whereby said folders have motion in unison, having provision for allowing one pair to move relatively to the other.

19. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, and devices for folding each section upon one of said portions, and provisions for automatically feeding the packages to said means, the said instrumentalities including a pair of folders for opposite sides of the package, a pair of folders for the other sides, and means whereby said folders have motion in unison, having provision for allowing one pair to move relatively to the other.

20. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package,

thereby forming outstanding sections of the material between said portions, and devices for folding each section upon one of said portions, and provisions for cutting the said sheet from a strip, operative to sever the material in advance of the operation of said clamp, the said instrumentalities including a pair of folders for opposite sides of the package, a pair of folders for the other sides, and means whereby said folders have motion in unison, having provision for allowing one pair to move relatively to the other.

21. The said machine (substantially as set forth in claim 1), said clamp having a stem extending longitudinally of said instrumentalities, in the direction of movement thereof, and a spring applied to said stem, serving to yieldingly hold the clamp against the package.

22. The said machine (substantially as set forth in claim 1), having provisions for simultaneously applying a similar cap to the other end of the package, said clamp having a stem extending longitudinally of said instrumentalities, in the direction of movement thereof, and a spring applied to said stem, serving to yieldingly hold the clamp against the package.

23. The said machine (substantially as set forth in claim 1), having provisions for applying an adhesive to the entire inner surface of said sheet before the same is fed into position, said clamp having a stem extending longitudinally of said instrumentalities, in the direction of movement thereof, and a spring applied to said stem, serving to yieldingly hold the clamp against the package.

24. The said machine (substantially as set forth in claim 1), having provisions for automatically feeding the packages to said means, said clamp having a stem extending longitudinally of said instrumentalities, in the direction of movement thereof, and a spring applied to said stem, serving to yieldingly hold the clamp against the package.

25. The said machine (substantially as set forth in claim 1), having provisions for cutting the said sheet from a strip, operative to sever the material in advance of the operation of said clamp, said clamp having a stem extending longitudinally of said instrumentalities, in the direction of movement thereof, and a spring applied to said stem, serving to yieldingly hold the clamp against the package.

26. The said machine (substantially as set forth in claim 1), said instrumentalities including a set of rollers movable toward and away from the package, operating on said sections while moving.

27. The said machine (substantially as set forth in claim 1), and provisions for simul-

taneously applying a similar cap to the other end of the package, said instrumentalities including a set of rollers movable toward and away from the package and operating 5 on said sections while moving.

28. The said machine (substantially as set forth in claim 1), and provisions for applying an adhesive to the entire inner surface of said sheet before the same is fed into position, 10 said instrumentalities including a set of rollers movable toward and away from the package and operating on said sections while moving.

29. The said machine (substantially as set 15 forth in claim 1), and provisions for automatically feeding the packages to said means, said instrumentalities including a set of rollers movable toward and away from the package and operating on said sections while moving.

30. The said machine (substantially as set forth in claim 1), and provisions for cutting the said sheet from a strip, operative to sever the material in advance of the operation 25 of said clamp, said instrumentalities including a set of rollers movable toward and away from the package and operating on said sections while moving.

31. A capping machine for sealing the 30 ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, and devices for folding each section upon one of said 35 portions, said devices including a plurality of pivoted fingers for engaging said sections, and means for controlling said fingers.

32. A capping machine for sealing the 40 ends of packages, comprising means for holding a package in position to receive the cap, mechanism for feeding sheet material on to the end of the package, a clamp for holding the sheet in position, instrumentalities for folding the marginal portions of 45 the sheet upon the sides of the package, thereby forming outstanding sections of the material between said portions, devices for folding each section upon one of said portions, provisions for simultaneously applying 50 a similar cap to the other end of the package, said devices including a plurality of pivoted fingers for engaging said sections, and means for controlling said fingers.

33. A capping machine for sealing the 55 ends of packages, comprising means for holding a package in position to receive the cap, mechanism for feeding sheet material on to the end of the package, a clamp for holding the sheet in position, instrumentalities for folding the marginal portions of 60

the sheet upon the sides of the package, thereby forming outstanding sections of the material between said portions, devices for folding each section upon one of said portions, provisions for applying an adhesive 70 to the entire inner surface of said sheet before the same is fed into position, said devices including a plurality of pivoted fingers for engaging said sections, and means for controlling said fingers. 75

34. A capping machine for sealing the ends of packages, comprising means for holding a package in position to receive the cap, mechanism for feeding sheet material on to the end of the package, a clamp for 80 holding the sheet in position, instrumentalities for folding the marginal portions of the sheet upon the sides of the package, thereby forming outstanding sections of the material between said portions, devices for 85 folding each section upon one of said portions, provisions for automatically feeding the packages to said means, said devices including a plurality of pivoted fingers for engaging said sections, and means for controlling said fingers. 90

35. A capping machine for sealing the ends of packages, comprising means for holding a package in position to receive the cap, mechanism for feeding sheet material 95 on to the end of the package, a clamp for holding the sheet in position, instrumentalities for folding the marginal portions of the sheet upon the sides of the package, thereby forming outstanding sections of the material 100 between said portions, devices for folding each section upon one of said portions, provisions for cutting the said sheet from a strip, operative to sever the material in advance of the operation of said clamp, said devices including a plurality of pivoted fingers for 105 engaging said sections, and means for controlling said fingers.

36. A capping machine for sealing the ends of packages, comprising means for 110 holding a package in position to receive the cap, mechanism for feeding sheet material on to the end of the package, a clamp for holding the sheet in position, instrumentalities for folding the marginal portions of 115 the sheet upon the sides of the package, thereby forming outstanding sections of the material between said portions, and devices for folding each section upon one of said portions, said instrumentalities having rollers for pressing said sections against the package, after the sections are folded by 120 said devices.

37. A capping machine for sealing the ends of packages, comprising means for 125 holding a package in position to receive the cap, mechanism for feeding sheet material on to the end of the package, a clamp for holding the sheet in position, instrumentalities for folding the marginal portions of 130 the

sheet upon the sides of the package, thereby forming outstanding sections of the material between said portions, devices for folding each section upon one of said portions, 5 and provisions for simultaneously applying a similar cap to the other end of the package, said instrumentalities having rollers for pressing said sections against the package, after the sections are folded by said 10 devices.

38. A capping machine for sealing the ends of packages, comprising means for holding a package in position to receive the cap, mechanism for feeding sheet material 15 on to the end of the package, a clamp for holding the sheet in position, instrumentalities for folding the marginal portions of the sheet upon the sides of the package, thereby forming outstanding sections of the material 20 between said portions, devices for folding each section upon one of said portions, and provisions for applying an adhesive to the entire inner surface of said sheet before the same is fed into position, said 25 instrumentalities having rollers for pressing said sections against the package, after the sections are folded by said devices.

39. A capping machine for sealing the ends of packages, comprising means for holding a package in position to receive the cap, mechanism for feeding sheet material 30 on to the end of the package, a clamp for holding the sheet in position, instrumentalities for folding the marginal portions of the sheet upon the sides of the package, thereby forming outstanding sections of the material 35 between said portions, devices for folding each section upon one of said portions, and provisions for automatically feeding the 40 packages to said means, said instrumentalities having rollers for pressing said sections against the package, after the sections are folded by said devices.

40. A capping machine for sealing the ends of packages, comprising means for holding a package in position to receive the cap, mechanism for feeding sheet material 45 on to the end of the package, a clamp for holding the sheet in position, instrumentalities for folding the marginal portions of the sheet upon the sides of the package, thereby forming outstanding sections of the material 50 between said portions, devices for folding each section upon one of said portions, and provisions for cutting the said sheet from a strip, operative to sever the material in advance of the operation of said clamp, said instrumentalities having rollers for pressing 55 said sections against the package, after the sections are folded by said devices.

41. A capping machine for sealing the ends of packages, comprising means for holding a package in position to receive the cap, mechanism for feeding sheet material 60 on to the end of the package, a clamp for

holding the sheet in position, instrumentalities for folding the marginal portions of the sheet upon the sides of the package, thereby forming outstanding sections of the material between said portions, and devices 70 for folding each section upon one of said portions, said devices including a plurality of pivoted fingers for engaging said sections, and means for operating said fingers about their pivots, carried by an element of said 75 instrumentalities.

42. A capping machine for sealing the ends of packages, comprising means for holding a package in position to receive the cap, mechanism for feeding sheet material 80 on to the end of the package, a clamp for holding the sheet in position, instrumentalities for folding the marginal portions of the sheet upon the sides of the package, thereby forming outstanding sections of the material 85 between said portions, devices for folding each section upon one of said portions, provisions for simultaneously applying a similar cap to the other end of the package, said devices including a plurality 90 of pivotal fingers for engaging said sections, and means for operating said fingers about their pivots, carried by an element of said instrumentalities.

43. A capping machine for sealing the 95 ends of packages, comprising means for holding a package in position to receive the cap, mechanism for feeding sheet material on to the end of the package, a clamp for holding the sheet in position, instrumentalities 100 for folding the marginal portions of the sheet upon the sides of the package, thereby forming outstanding sections of the material between said portions, devices for folding 105 each section upon one of said portions, provisions for applying an adhesive to the entire inner surface of said sheet before the same is fed into position, said devices including a plurality of pivoted fingers for engaging 110 said sections, and means for operating said fingers about their pivots, carried by an element of said instrumentalities.

44. A capping machine for sealing the ends of packages, comprising means for holding a package in position to receive the 115 cap, mechanism for feeding sheet material on to the end of the package, a clamp for holding the sheet in position, instrumentalities for folding the marginal portions of the sheet upon the sides of the package, thereby 120 forming outstanding sections of the material between said portions, devices for folding each section upon one of said portions, provisions for automatically feeding the packages to said means, said devices including a 125 plurality of pivoted fingers for engaging said sections, and means for operating said fingers about their pivots, carried by an element of said instrumentalities.

45. A capping machine for sealing the 130

ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for cutting the said sheet from a strip, operative to sever the material in advance of the operation of said clamp, said devices including a plurality of pivoted fingers for engaging said sections, and means for operating said fingers about their pivots, carried by an element of said instrumentalities.

46. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, and devices for folding each section upon one of said portions, said means including a spring-backed plate for holding the package down, a pivoted stop for the package, and a spring for holding said stop in position.

47. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for simultaneously applying a similar cap to the other end of the package, said means including a spring-backed plate for holding the package down, a pivoted stop for the package, and a spring for holding said stop in position.

48. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for applying an adhesive to the entire inner surface of said sheet before the same is fed into position, said means including a spring-backed plate for holding the

package down, a pivoted stop for the package, and a spring for holding said stop in position.

49. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for automatically feeding the packages to said means, said means including a spring-backed plate for holding the package down, a pivoted stop for the package, and a spring for holding said stop in position.

50. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for cutting the said sheet from a strip, operative to sever the material in advance of the operation of said clamp, said means including a spring-backed plate for holding the package down, a pivoted stop for the package, and a spring for holding said stop in position.

51. The said machine (substantially as set forth in claim 1), said mechanism including a reciprocating device having jaws for gripping and pulling the sheet across the end of the package and means for automatically opening and closing said jaws.

52. The said machine (substantially as set forth in claim 1), and provisions for simultaneously applying a similar cap to the other end of the package, said mechanism including a reciprocating device having jaws for gripping and pulling the sheet across the end of the package and means for automatically opening and closing said jaws.

53. The said machine (substantially as set forth in claim 1), and provisions for applying an adhesive to the entire inner surface of said sheet before the same is fed into position, said mechanism including a reciprocating device having jaws for gripping and pulling the sheet across the end of the package and means for automatically opening and closing said jaws.

54. The said machine (substantially as set forth in claim 1), and provisions for automatically feeding the packages to said

means, said mechanism including a reciprocating device having jaws for gripping and pulling the sheet across the end of the package and means for automatically opening and closing said jaws.

55. The said machine (substantially as set forth in claim 1), and provisions for cutting the said sheet from a strip, operative to sever the material in advance of the operation of said clamp, said mechanism including a reciprocating device having jaws for gripping and pulling the sheet across the end of the package and means for automatically opening and closing said jaws.

56. The said machine (substantially as set forth in claim 1), and a shaft disposed at the bottom of the machine and connected for operating all of said elements.

57. The said machine (substantially as set forth in claim 1), and provisions for simultaneously applying a similar cap to the other end of the package, and a shaft disposed at the bottom of the machine and connected for operating all of said elements.

58. The said machine (substantially as set forth in claim 1), and provisions for applying an adhesive to the entire inner surface of said sheet before the said sheet is fed into position, and a shaft disposed at the bottom of the machine and connected for operating all of said elements.

59. The said machine (substantially as set forth in claim 1), and provisions for automatically feeding the packages to said material means, and a shaft disposed at the bottom of the machine and connected for operating all of said elements.

60. The said machine (substantially as set forth in claim 1), and provisions for cutting the said sheet from a strip, operative to sever the material in advance of the operation of said clamp, and a shaft disposed at the bottom of the machine and connected for operating all of said elements.

61. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, said devices including a plurality of fingers pivoted to swing in planes parallel with the package, means for operating said fingers, carried by said instrumentalities, and stationary means for restoring said fingers to normal position, disposed in position to engage the rear ends thereof.

62. A capping machine for sealing the ends of packages, comprising means for

holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for simultaneously applying a similar cap to the other end of the package, said devices including a plurality of fingers pivoted to swing in planes parallel with the package, means for operating said fingers, carried by said instrumentalities, and stationary means for restoring said fingers to normal position, disposed in position to engage the rear ends thereof.

63. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for applying an adhesive to the entire inner surface of said sheet before the same is fed into position, said devices including a plurality of fingers pivoted to swing in planes parallel with the package, means for operating said fingers, carried by said instrumentalities, and stationary means for restoring said fingers to normal position, disposed in position to engage the rear ends thereof.

64. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material between said portions, devices for folding each section upon one of said portions, provisions for automatically feeding the packages to said means, said devices including a plurality of fingers pivoted to swing in planes parallel with the package, means for operating said fingers, carried by said instrumentalities, and stationary means for restoring said fingers to normal position, disposed in position to engage the rear ends thereof.

65. A capping machine for sealing the ends of packages, comprising means for holding a package in position to receive the cap, mechanism for feeding sheet material on to the end of the package, a clamp for holding the sheet in position, instrumentalities

ties for folding the marginal portions of the sheet upon the sides of the package, thereby forming outstanding sections of the material between said portions, devices for 5 folding each section upon one of said portions, provisions for cutting the said sheet from a strip, operative to sever the material in advance of the operation of said clamp, said devices including a plurality of fingers 10 pivoted to swing in planes parallel with the package, means for operating said fingers, carried by said instrumentalities, and stationary means for restoring said fingers to normal position, disposed in position to engage 15 the rear ends thereof.

66. The said machine (substantially as set forth in claim 1), said means supporting the package in horizontal position, with the end of the package projecting free and 20 clear, and said mechanism being operative to feed the sheet edgewise and downward.

67. The said machine (substantially as set forth in claim 1), and provisions for 25 simultaneously applying a similar cap to the other end of the package, said means supporting the package in horizontal position, with the end of the package projecting free and clear, and said mechanism being operative to feed the sheet edgewise and 30 downward.

68. The said machine (substantially as set forth in claim 1), and provisions for applying an adhesive to the entire inner surface of said sheet before the same is fed 35 into position, said means supporting the package in horizontal position, with the end of the package projecting free and clear, and said mechanism being operative to feed the sheet edgewise and downward.

40 69. The said machine (substantially as set forth in claim 1), and provisions for automatically feeding the packages to said means, said means supporting the package in horizontal position, with the end of the 45 package projecting free and clear, and said mechanism being operative to feed the sheet edgewise and downward.

70. The said machine (substantially as set forth in claim 1), and provisions for cutting the said sheet from a strip, operative to sever the material in advance of the operation of said clamp, said means supporting the package in horizontal position, with the end of the package projecting free and 55 clear, and said mechanism being operative to feed the sheet edgewise and downward.

71. A capping machine for sealing the ends of packages, comprising means for holding a package in position to receive the 60 cap, mechanism for feeding sheet material on to the end of the package, a clamp for holding the sheet in position, instrumentalities for folding the marginal portions of the sheet upon the sides of the package, thereby 65 forming outstanding sections of the mate-

material between said portions, devices for folding each section upon one of said portions, and a vertically reciprocating member for supporting a series of packages operating to successively deliver the packages 70 to the machine.

72. A capping machine for sealing the ends of packages, comprising means for holding a package in position to receive the cap, mechanism for feeding sheet material 75 on to the end of the package, a clamp for holding the sheet in position, instrumentalities for folding the marginal portions of the sheet upon the sides of the package, thereby forming outstanding sections of the material 80 between said portions, devices for folding each section upon one of said portions, provisions for simultaneously applying a similar cap to the other end of the package, and a vertically reciprocating member for supporting a series of packages operating 85 to successively deliver the packages to the machine.

73. A capping machine for sealing the ends of packages, comprising means for holding a package in position to receive the cap, mechanism for feeding sheet material 90 on to the end of the package, a clamp for holding the sheet in position, instrumentalities for folding the marginal portions of the sheet upon the sides of the package, thereby forming outstanding sections of the material 95 between said portions, devices for folding each section upon one of said portions, provisions for applying an adhesive to the entire inner surface of said sheet before the same is fed into position, and a vertically reciprocating member for supplying a series of packages operating to successively deliver 100 the packages to the machine.

74. A capping machine for sealing the ends of packages, comprising means for holding a package in position to receive the cap, mechanism for feeding sheet material on to the end of the package, a clamp for holding the sheet in position, instrumentalities for folding the marginal portions of the sheet upon the sides of the package, thereby forming outstanding sections of the material 110 between said portions, devices for folding each section upon one of said portions, provisions for automatically feeding the packages to said means, and a vertically reciprocating member for supporting a series of packages operating to successively 115 deliver the packages to the machine.

75. A capping machine for sealing the ends of packages, comprising means for holding a package in position to receive the cap, mechanism for feeding sheet material 125 on to the end of the package, a clamp for holding the sheet in position, instrumentalities for folding the marginal portions of the sheet upon the sides of the package, thereby forming outstanding sections of the mate- 130

rial between said portions, devices for folding each section upon one of said portions, provisions for cutting the said sheet from a strip, operative to sever the material in advance of the operation of said clamp, and a vertically reciprocating member for supporting a series of packages operating to successively deliver the packages to the machine.

10 76. A machine for capping packages, comprising a feed belt and guide for delivering the packages to the machine, a pusher reciprocating horizontally below the lower end of said guide, for pushing the packages 15 into the machine, and a member reciprocating up and down below said guide, serving to control the delivery of packages to said pusher, together with means for capping the packages, disposed in position to receive the 20 package from said pusher, and said pusher operating to cause each package when capped to be pushed out of the machine by the one behind.

25 77. A machine for capping packages, comprising a support for the package, means for sliding the packages bodily over said support, a yielding stop at the front edge of said support, to hold the package in place, a yielding clamp for the upper side 30 of the package, whereby the package is held in place with the ends thereof projecting free and clear, and means for capping the ends of the package, together with means for pushing the finished package over said 35 stop.

40 78. A machine for capping packages, comprising means for holding the package in horizontal position, guides for directing sheets of paper downwardly across the opposite ends of said package, stationary knives disposed in position between said sheets, each guide having a depending member for holding the sheet in position, pivoted at its upper end, disposed over said 45 knives, movable knives disposed below said guides, outside of said sheets, means for gripping the sheets and pulling the same downward, and means for operating said movable knives.

50 79. A machine for capping packages, comprising means for holding the package in position and for retaining the package in said position during the entire capping operation, and mechanism for folding a flat sheet of paper upon the end of the package, to form a cap therefor, said mechanism comprising means for folding and holding the sides of the cap in place, devices for folding the corner sections of the cap, and means for 55 pressing said corner sections against the package.

60 80. A machine for capping packages, comprising means for holding the package in position, and mechanism for folding a flat sheet of paper upon the end of the

package, to form a cap therefor, said mechanism comprising a movable member having means for folding two opposite sides of the cap, a movable member having means for folding the other sides of the cap, fingers 70 pivoted on one of said members, disposed in position to fold the corner sections of the cap, means on the other member for engaging said fingers, causing the operation thereof, means for pressing said corner sections upon the package, disposed in position to follow said fingers in the backward movement thereof, means for operating said members, one member being movable relatively to the other, and stationary means 75 for engaging the rear ends of said fingers, serving thereby to restore said fingers to normal position.

81. A machine for capping packages, comprising means for holding the package 85 in position to receive the cap, means for completely folding a sheet of paper upon the end of the package while in said position, to form the cap, means for feeding the paper across the end of the package, a movable knife for severing the paper, a toggle joint between said knife and member, serving to operate said knife, a stationary support, and a link extending laterally from said toggle joint, pivoted on said support. 90

82. A machine for capping packages, comprising a pair of relatively movable members, one member extending parallel with the other, both mounted to move endwise, a spring through which one member 10 moves the other, serving to permit the one member to continue moving after the other stops, means on one member for folding two opposite sides of the cap, means on the other member for folding the other sides of 105 the cap, and means for folding the corners of the cap, mounted on the one member, together with means for pressing said corners against the package, mounted on the other member. 110

83. A machine for capping packages, comprising means to hold the package stationary in one position during the entire capping operation, mechanism for folding the sides of the cap, devices for folding the 115 corner sections of the cap, and means for pressing the sections against the sides.

84. The said machine (substantially as set forth in claim 83) said means being disposed in position to engage the sections 120 while returning to normal position.

85. The said machine (substantially as set forth in claim 83), said means serving by the initial engagement thereof to push the edge portions of the sections into direct 125 contact with the package.

86. The said machine (substantially as set forth in claim 83), said devices being disposed in position to fold the sections toward each other at opposite sides of the package.

87. A machine for capping packages, comprising means for holding the package in position, mechanism for feeding a sheet of paper across the end of the package, and means for folding the sheet to form the cap, said mechanism comprising a pair of jaws for gripping the paper, a tube to which one jaw is secured, a member in said tube, supporting said other jaw, and means for reciprocating said jaws, having cam devices for causing relative movement between said tube and member, serving to open and close said jaws.

88. A machine for capping packages, comprising means for holding the package in position, means for feeding a sheet of paper across the end of the package, means for cutting off the end portion of the sheet, means for folding the severed section of paper upon the end of the package, and mechanism for applying an adhesive to the entire inner surface of said sheet, including rolls for engaging the sheet, means for operating said rolls, means for supplying the adhesive to one roll, and a device for shifting the other roll to release the sheet, said device comprising a pivoted member, means for engaging said member, carried on the ends of said other roll, and springs acting in opposition to said device, serving to yieldingly hold said other roll in operative position.

89. A machine for capping packages, comprising means for feeding a sheet of paper across the end of the package, operating intermittently, means for cutting off the end portion of the sheet, and mechanism for feeding the sheet continuously, having provisions for applying an adhesive thereto, before the sheet reaches said cutting means, and means for folding the severed portion of the sheet upon the end of the package, and a device for supporting the end of the sheet during the operation of said folding means.

90. A machine for capping packages, comprising means for feeding a sheet of paper across the end of the package, operating intermittently, means for cutting off the end portion of the sheet, and mechanism for feeding the sheet continuously, having provisions for applying an adhesive thereto, before the sheet reaches said cutting means, and means for folding the severed portion of the sheet upon the end of the package, said intermittent feeding means serving to pull the loose end portion of the sheet downward, after each operation of said folding means.

91. A machine for capping packages, comprising mechanism for automatically feeding the packages into position, means for capping the end of the package, yielding

means for holding the package in position, and a continuously operating belt for throwing the finished package out of the machine, said mechanism serving to push the finished package on to said belt by the feeding of another package into position.

92. A capping machine comprising folding mechanism, mechanism for cutting the paper for the cap, including a movable member provided with a blade, a device for pulling the paper down, movable above the said member to grip the paper, and means for operating said folding mechanism to fold the severed sheet into a cap for the end of the package.

93. The said machine (substantially as set forth in claim 92), said member having a notch through which said device moves upward but not downward.

94. The said machine (substantially as set forth in claim 92), said member being movable backward before the said device moves downward.

95. In a capping machine, package-holding and cap-applying mechanism comprising means for holding the package in one position during the entire operation of applying the cap thereto, means for feeding sheet material to said position, means for cutting off a rectangular section of said material, and means for holding the section and creasing the corners thereof to form said cap.

96. In a capping machine, package-holding and cap-applying mechanism comprising means for holding the package in one position during the entire operation of applying the cap thereto, means for applying an adhesive to sheet material, means for feeding said material to said position, means for cutting off a rectangular section of said material, means for folding the edges of the section upon the sides of the package, with the adhesive surface of the section inside, means for folding the corner portions of the section upon the sides of the cap, and means for causing an uncapped package to displace the capped package from said position.

97. In a capping machine, package-holding and cap-applying mechanism comprising means for holding the package in one position during the entire operation of applying the cap thereto, and means for causing an uncapped package to displace the capped package from said position.

Signed by me at St. Joseph, Michigan, this 13th day of January, 1914.

EDWARD CRAIG.
